CLEANER FOR HEAT EXCHANGE AND
LIKE TUBESVirgil H. Baker, Springfield, Ohio, assignor to
Elliott Company, Pittsburgh, Pa., a corporation
of Pennsylvania

Application December 22, 1947, Serial No. 793,169

9 Claims. (Cl. 15—104.14)

1

This invention pertains to tube cleaners, and more particularly to a swing frame cutter head for tube cleaning equipment.

The general type of cutter head shown herein, and commonly known as a swing frame or swinging arm cutter head, is in everyday use by industry. There are, however, certain inherent disadvantages in the structural arrangement of the component parts comprising the presently used cutter heads. Such disadvantages have been heretofore known, and many efforts made to eliminate such deficiencies. Due to the type of cutter head which is subjected to centrifugal force, extreme pressures are created within the parts of the head, making such cutters subject to excessive wear and breakage. Many different constructions have been proposed and used in an effort to reduce this excessive wear and breakage to a minimum, none of which, however, have been wholly successful. The present invention is directed to a structure which under actual working conditions has completely eliminated the heretofore objectionable breakage and excessive wear.

The object of the invention therefore is to improve the construction as well as the means and mode of operation of centrifugally actuated cutter heads, whereby they may not only be economically manufactured, but will be more efficient in operation, uniform in action, of longer life, and be unlikely to get out of repair.

A further object of the invention is to improve the construction of such cutter heads whereby excessive strains are eliminated.

A further object of the invention is to provide a construction in which torsional and shearing strains upon the parts of the head are reduced to a minimum.

A further object of the invention is to provide a construction in which the critical elements are subjected to compressive forces while the head is under the influence of centrifugal force.

A further object of the invention is to provide a locking member usable in such cutter heads which effectively prevents longitudinal and rotational movement of its associated member.

A further object of the invention is to provide locking means in such cutter heads having relatively few parts which may be quickly and easily assembled.

A further object of the invention is to provide a centrifugally operated cutter head having the advantageous features, the inherent meritorious characteristics and the mode of operation, or their equivalents, as hereinafter described or shown in the accompanying drawing.

2

With the above primary and other incidental objects in view as will more fully appear in the specification, the invention intended to be protected by Letters Patent consists of the features of construction, the parts and combinations thereof, and the mode of operation, as hereinafter described or illustrated in the accompanying drawings, or their equivalents.

10 In the drawing, wherein is shown the preferred but obviously not the only embodiment of the invention,

Fig. 1 is a perspective view of a centrifugally operated cutter head embodying the present invention.

15 Fig. 2 is a fragmentary side elevation, partly in section, of a cutter head embodying the present invention.

Fig. 3 is a fragmentary sectional view taken on line 3—3 of Fig. 2.

20 Fig. 4 is a perspective view of the locking member.

Like parts are indicated by similar characters of reference throughout the several views.

25 Referring to the drawings, there is shown in Fig. 1 a perspective view of a centrifugally actuated cutter embodying the present invention and comprising a central frame member or spider 1 upon which the remaining parts of the head are pivotally supported. Each end of the spider has

30 a series of longitudinally aligned radially projecting lobes 2—3 thereon which serve as the mounting means for the swinging arms. Supported between the lobes 2—3 upon arm pins 4 are

35 swinging arms 5, comprising a substantially U-shaped member having a central portion 6 and transversely extending terminal members 7—8. The swinging arm 5 is pivotally secured between each pair of lobes 2—3 upon the arm pin 4 which passes through aligned bores within the lobes 2—3 and the central portion 6 of the arm.

40 The transversely extending terminal members 7—8 of the swinging arm 5 have aligned bores in their outer extremities through which pass cutter pins 9 having enlarged heads 10 thereon. A series of freely rotating cutters 11 and 12 are

45 mounted upon the cutter pins 9, the tapered cutter 11 being mounted on the pin in engagement with the head 10 before the pin is passed through the front member 8. The series of straight cutters 12 are then assembled on the pin and the pin then passed through the rear terminal member 7.

The arm 5 with the cutters assembled thereon is then placed in the spider and the arm pins 4 inserted to mount the arms on the spider. A head coupling 13 is then assembled on the spider

1, a flange 14 upon the coupling engaging the heads 15 upon the arm pins 4 to retain the pins in assembled position.

The head coupling 13 is attached to an appropriate source of power to rotate the cutter head. Upon rotation thereof the arms 5 swing outwardly under centrifugal influence thereby engaging the cutters 11 and 12 with the interior walls of a tube being cleaned. The cutters are rotated upon the cutter pins by the frictional engagement thereof with the tube wall. The speed of rotation of the spider 1 being relatively high, the rotational speed of the cutters upon the cutter pins becomes considerably greater, creating great stress upon the cutter pins and the terminal member of the swinging arms. 10

The cutter pins 9 have the greatest strain, and are subject to the greatest wear due to the high speed rotation of the cutters thereon. If unanchored, the pins 9 of course would tend to 20 revolve with the cutters, causing excessive wear not only to the pins 9 but to the swinging arms 5. For this reason, the pins 9 must be restrained, and more or less locked in position within the swinging arms 5.

Various methods and structures have been proposed to accomplish this locking or holding of the cutter pins, all of which have striven to produce a fixed locking means that would prevent all movement of the pins relative to the swinging arms 5. This, however, has never proven satisfactory, since if positively held in position, the pins in a very short time crack or break due to metal fatigue caused by the vibration of the pin relative to a fixed point. Such locks have taken the form of nuts threaded on the cutter pins, or the threading of the cutter pins into the rear member 7 of the swinging arm 5.

Other means of locking the pins have been proposed such as substantially C-shaped locking plates for engagement with recessed or flattened terminals on the pins. This form of locking means has proven very unsatisfactory since the furcations of the locking plate between which the pin is located very soon weaken and break under the continuous torsional and shearing strain placed thereon by the attempted rotation of the cutter pin.

The various disadvantages of these prior assemblies have been overcome by a relatively simple, but quite effective locking member which is so installed within the assembly comprising the cutter head that the member is subjected only to compressive forces, resistance to which forces represents the greatest strength of the locking member. The described locking member functions as a latch in connection with the cutter pin, and, since it is interposed between the cutter and arm pins, may be described as a third pin. 50

The outer faces of the rear terminal members 7 of the swinging arms 5 are recessed as shown at 15, such recess interconnecting the transverse bores through which the cutter pins 9 and arm pins 4 extend. The width of the recess 15 is substantially equal to the diameter of the transverse bore through which the arm pin 4 extends. 55

The cutter pin 9 has a transverse notch 16 so located therein as to be in substantial alignment with the recess 15 when the pin 9 is fully inserted through the terminal members 7 and 8 of the swinging arm 5.

A locking member or bar 17, shown in Fig. 4, having a rectangular terminal or terminal end 18 and a concave semi-circular terminal or ter- 60

65 minal end 19 at its opposite end is so proportioned as to fit within the recess 15 of the terminal member 7 on the arm 5. The length of the locking bar 17 is such that when the terminal 18 thereof is seated within the notch 16 in the cutter pin 9, the opposite terminal 19 thereof is located in concentric relation with the transverse bore through which the arm pin 4 projects. The radius of curvature of the semi-circular terminal 19 is substantially equal to the radius of the bore within the member 7.

In assembling the unit, the cutters 11-12 are assembled upon the cutter pin 9 as before explained and the pin inserted in its supporting bores within the terminal members 7-8 of the arm 5. The locking member 17 is then placed in the recess 15, the rectangular terminal 18 thereof being adjacent the cutter pin 9. The bar 17 is then moved so that the terminal 19 thereof enters the notch 16 in the pin 9, thereby aligning the opposite semi-circular terminal 19 with the bore through which the arm pin 4 projects. The arm is then placed intermediate the lobes 2-3 on the spider 1 in alignment with the transverse bores therein and the arm pin 4 inserted therethrough. The pins 4 are retained in position by the coupling head 13 and associated flange 14.

Upon assembly of the arm 5 carrying the cutter pin 9 and locking bar 17 within the lobes 2-3 of the spider 1, the locking member 17 is retained within the recess 15 by the overlapping engagement of the lobes 2-3 therewith. Movement of the locking member 17 longitudinally of the cutter head is thereby effectively prevented. Simultaneously with the assembly of the arm 5 to the spider 1, the rectangular terminal 18 of the locking member enters the notch 16 in the cutter pin 9 and is retained therein by the arm pin 4 upon which the semi-circular terminal 19 of the locking member rests. 30

Longitudinal movement of the cutter pin 9 is thereby prevented by the retention of the locking member 17 within the recess 15 and the overlapping engagement of the notch 16 relative to the terminal 18 of the locking member. Rotational movement of the cutter pin 9 is also prevented by the engagement of the locking member 17 within the notch 16. 45

Such rotational movement causes the greatest strain upon the locking member since the forces created by the rapid rotation of the cutters 11-12 on the pin 9 are considerably greater than the tendency for the pin 9 to move longitudinally of the cutter head. Such excessive force is transmitted to the locking member 17 in such a fashion that the locking member is placed in compression rather than creating a shearing or torsional strain therein. The reaction of the force applied to the locking member 17 upon rotational movement of the pin 9 is fully taken by the arm pin 4 upon which the semi-circular terminal 19 of the locking member is supported and the side of the recess 15. By such construction, the greatest strength of the locking member 17, namely compression, is utilized. 55

Although the locking member 17 effectively prevents both longitudinal and rotational movement of the cutter pin 9, such locking or holding of the pin is not in the sense of an absolute and fixed locking thereof as would result upon threaded engagement of the pin with the terminal member 7 or by locking the pin by means of a bolt engaged therewith. Sufficient looseness or 60 play is permitted so that the cutter pin 9 will not

break from fatigue caused by continued vibration and strain opposed by an absolutely fixed mounting of the pin within the terminal member 7.

The present construction has been found quite satisfactory in actual use, it being far superior to the more conventional assemblies embodying means for fixedly securing the cutter pin 9 to the swinging arm 5. A cutter head having a longer life, with fewer replacements and repairs has resulted from the use of the present structural features in such equipment.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown; but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. In a tube cleaner of the swinging arm type having an arm pin upon which the arm is pivotally mounted and a series of freely rotatable cutters carried by a cutter pin normally loosely mounted within the swinging arm, means for locking the cutter pin against longitudinal and rotational movement relative to its supporting arm, including a bar, a rectangular terminal on one end thereof, a concave semi-circular terminal on the opposite end thereof, a recess in the swinging arm within which the bar is seated intermediate the cutter pin and arm pin with the concave semi-circular terminal thereof in engagement with the arm pin, means for engaging the rectangular terminal of the bar with the cutter pin including a transverse notch in the cutter pin in alignment with the recess within which notch the bar is engageable upon engagement of the arm pin therewith, the surfaces of the notch and the terminal end of the bar so shaped that the bar is subjected to compressive forces only upon attempted rotational movement of the cutter pin relative thereto, and means for holding said bar in said recess upon assembly of the swinging arm upon the arm pin.

2. A tube cleaner of the type wherein a series of revoluble cutters are loosely mounted upon a cutter pin supported upon a centrifugally actuated swinging arm pivotally secured to a mounting head by a removable arm pin in parallel spaced apart relation to the cutter pin, characterized by a bar transversely disposed between the cutter pin and arm pin, interengaging configurations on the terminals of the bar and adjacent pins, one terminal end of the bar resting upon the periphery of one pin, a transverse notch in the other pin within which the opposite terminal end of the bar rests, and a recess in the swinging arm within the confines of which the bar is located to prevent both lateral and angular displacement of the bar, the surfaces of the transverse notch and the terminal end which is en-

gaged thereby being such that rotational movement of one of the pins is prevented and the forces created thereby absorbed by compressive reaction of the bar thereagainst.

- 5 3. In a tube cleaner of the character described having relatively spaced parallel cutter and arm pins and supporting means therefor, a member interposed between said pins with one terminal end in abutting engagement with the arm pin, a transverse notch in said cutter pin receiving the opposite terminal end of said member, the surfaces of said opposite terminal end and the notch being so shaped to preclude relative rotational movement of the pin, the force exerted by the cutter pin thereon being transferred to the member in the form of direct thrust pressure, the reaction to which is provided by the arm pin through direct thrust engagement of the member therewith.
- 10 4. In a tube cleaner of the character described having relatively spaced parallel cutter and arm pins and supporting means therefor, a locking member therefor whereby rotational movement of the cutter pin is prevented, characterized by an elongated bar transversely disposed intermediate the cutter and arm pins, a transverse notch in one of the pins within which one terminal end of the bar is seated for a resolving of rotational impulses of said pin into an axial thrust of said bar, the surfaces of said one terminal end of the bar and the notch being so shaped to preclude relative rotational movement of the pin, a semi-circular terminal on the opposite end of the bar the radius of which is substantially equal to the radius of the other pin upon the periphery of which the semi-circular terminal of the bar rests in abutting engagement therewith.

- 15 5. In a centrifugally operated tube cleaner having relatively spaced cutter and arm pins transfixing a swinging arm assembly, supporting means for said pins, means for locking the cutter pin against both longitudinal and rotative movement, including a transverse notch in the periphery of the cutter pin, a locking bar having one terminal end seated within such notch, a thrust seat upon the opposite terminal end of the bar having abutting engagement with the periphery of the arm pin, the surfaces of the notch and the terminal end seated therein being so shaped that the thrust created by rotative movement of the cutter pin is equalized by the reactive force of the arm pin exerted through the locking bar, and a recess within the swinging arm within which the bar is confined to prevent movement thereof longitudinally of the arm pin in one direction.

- 20 6. A device of the class described having a pair of parallel relative spaced pivot pins mounted in a common support and normally revoluble one relative to the other, characterized by a third pin transversely disposed relative to the pair of pivot pins, one terminal end of said third pin being received in interlocking engagement within a transverse notch having a surface conforming to the surface of said one terminal end and formed in the opposite terminal end of said third pin having abutting engagement upon the other of said pivot pins, the surfaces of the notch and the terminal end seated therein so shaped as to preclude relative rotational movement of the pin, and an enclosure within the common support within which the third pin is retained in relatively fixed relation therewith.

- 25 7. In a tube cleaner of the character described having relatively spaced parallel cutter and arm pins and supporting means therefor, a latch

member extending endwise between said pins, said member having its one terminal end seated on the periphery of said arm pin in abutting engagement therewith and extending radially toward said cutter pin, and interengaging portions on said cutter pin and the opposite terminal end of said latch member, the surface portions of the cutter pin and the opposite terminal end so shaped as to resolve a rotary impulse of said cutter pin into an axial thrust upon said latch member, the said interengaging portion on said cutter pin including a transverse notch in the periphery thereof receiving the said opposite terminal end of said latch member and having a surface conforming thereto.

8. A device of the class described having a pair of parallel relatively spaced pivot pins mounted in a common support, a latch member extending endwise between said pivot pins, a connection between one of the terminal ends of said latch member and one of said pins resolving a rotatable impulse in said one pin into an axial thrust of said latch member, said connection including a transverse notch in the periphery of said one

pin receiving the said one terminal end of said latch member, the surface of the notch and the terminal end engaged therein so shaped as to prevent rotational movement of the one pin and a bearing surface in the opposite terminal end of said latch member in abutting engagement with said other pin for the absorption by said other pin of said axial thrust.

10 9. A device according to claim 8, characterized by a recess mounting for said latch member in said support precluding lateral shifting motion of said member.
